UNITED STATES PATENT OFFICE

LESLIE D. BOWERS, OF STREATOR, ILLINOIS

ELECTROMAGNETIC MEANS FOR CONTROLLING AIR BRAKES

Application filed March 8, 1928. Serial No. 260,055.

This invention has for its object the provision of means whereby air brakes may be operated electrically without affecting the usual pneumatic operation, and a particular object of the invention is to provide means whereby the brakes upon a long train may be operated instantly throughout the length of the train and the serial operation, which is present in the pneumatic control, will be avoided. Another object of the invention is to provide means whereby an emergency application of the brakes will be more effectual than the emergency application by the pneumatic means, and a further object of the invention is to provide an electric controlling mechanism which may be added to the standard equipment and operated without affecting the operation of the standard pneumatic equipment. The invention is illustrated in the accompanying drawings and will be hereinafter fully set forth and defined.

In the drawings:

Figure 1 is a diagram of an air brake system having the electric mechanism applied thereto;

Fig. 2 is an enlarged sectional elevation of the controlling valve and the means for setting the same;

Fig. 3 is an elevation of the controlling lever;

Fig. 4 is an end elevation, partly broken away and in section, of the controlling lever;

Fig. 5 is an enlarged transverse section of a portion of the means for setting the valve;

Figs. 6, 7, 8, 9 and 10 are enlarged longitudinal sections showing different positions of the valve;

Fig. 11 is a bottom plan view of the valve;

Fig. 12 is a top plan view of the valve block or bed plate;

Fig. 13 is an enlarged section of a non-return check valve which is employed;

Figs. 14 and 15 are sections of a double check valve which is employed in the apparatus;

Fig. 16 is a longitudinal section of the coupling employed to connect the electric cables upon two adjacent cars, and

Fig. 17 is an end elevation of such coupling.

Referring to Fig. 1, the reference numeral 1 indicates an air compressor which is mounted upon the locomotive and supplies air under pressure to the main storage reservoir 2 from which the air passes to the train line 3 through an engineer's valve 4 which is mounted in the cab of the locomotive. Upon the tender and each car in the train, a branch pipe 5 leads from the train line to a triple valve 6 to deliver compressed air into an auxiliary reservoir 7. The air within the auxiliary reservoir passes through the triple valve into a pipe 8 which leads it to the brake cylinder 9 within which is a piston acting directly upon a lever 10 to apply the brake shoes 11 to the car wheels, indicated at 12. The train line 3 is provided at the ends of each car with flexible hose 13 whereby the several cars may be coupled together and the air from the main reservoir supplied to the entire system. All these mentioned parts are standard equipment and are shown in a conventional diagrammatic manner only inasmuch as the present invention involves no change in the operation thereof. It may be noted that, while various types of this standard equipment are in use, the variations consist in details of construction and the operation of all the types is substantially the same.

In carrying out the present invention, there is provided an additional tank or reservoir 14 which I will term an emergency reservoir and the branch pipe 5 is extended so as to supply air to this emergency reservoir, a non-return check valve 15 being interposed in the extension 16 of the branch pipe. The reservoir 14 should have a capacity about three and one-half times that of the auxiliary reservoir, in order to supply a high brake cylinder pressure, although the train line might be depleted or even exhausted. There is also provided a valve casing 17 within which is mounted a slide valve 18 which will be presently more particularly described. As shown in Fig. 1, the branch pipe 5 has a lateral terminal portion 19 which delivers air to the triple valve 6 and from this lateral portion a pipe 20 extends to a port 21 leading upwardly through the bed plate or block 22

of the valve casing. Adjacent the port 21, a port 23 is formed through the block 22, and this port 23 communicates through a pipe 24 with the auxiliary reservoir 7. A pipe 25 is connected with the emergency reservoir 14 and also with a port 26 in the valve block or bed 22 and alongside said port 26 a port 27 is formed in the valve block to deliver air through a pipe 28 to the brake cylinder 9 whereby to effect an emergency application of the brakes. A port 29 in the valve bed or block 22 communicates with the outside air, as indicated by the dotted lines in Fig. 12, so that this port constitutes an exhaust port. There is also a port 30 formed through the bed or valve block, and this port communicates through a pipe 31 with the auxiliary reservoir 7 while adjacent the port 30 a port 32 is formed through the valve block to communicate through a pipe 33 and a double check valve 34 with the brake cylinder 9. Between the port 32 and the end of the valve block is an exhaust port 35 which communicates with the atmosphere, as indicated by the dotted lines in Fig. 12.

The valve 18, as shown clearly in Figs. 2, 6, 7, 8, 9 and 10, is a slide valve having recesses 36, 37 and 38 in its under side which are adapted to operatively connect the respective ports in the operation of the apparatus as will hereinafter fully appear, and springs 39 interposed between the slide and the top of the valve casing serve to maintain the valve close to its seat so that the proper operation of the parts will be assured. Extending from one end of the valve through the adjacent end of the valve casing is a bar 40 having a rack 41 formed on its upper side at its outer end portion. Mounted in a bracket 42 which is secured upon the car is a shaft 43 to which is secured a pinion 44 meshing with the rack 41 whereby, when the shaft 43 is turned, a horizontal movement will be imparted to the rack and the slide. Also secured upon the shaft 43 is an arm or armature 45 which has its lower portion enlarged, as shown at 46, the enlargement serving as a counter-weight to balance the arm so that it will tend to remain in any position in which it may be set. Mounted upon the upper portion of the bracket 42, in an arc concentric with the shaft 43, are five electro-magnets 47, 48, 49, 50 and 51 which, when energized, will attract the armature arm 45 and thereby set the valve in a desired position. As shown most clearly in Fig. 5, the several electro-magnets are secured to an overhanging flange 52 at the upper edge of the bracket 42 by screws 53 which are insulated from the bracket by filling or bushing 54 of any suitable material. The several magnets receive current over separate wires but have a common return wire, indicated at 55, which extends along the outer edge of the flange 52 and is connected to the several magnets by branches 56 which constitute the ends of the

magnet windings. The leading-in wires and the return wire 55 are carried through the length of the train in a cable 56' which is provided, at each end of each car or unit of the train, with a coupling 57 which will be presently more particularly set forth. The current for energizing the magnets is supplied from a generator 58 mounted upon the locomotive and which may be a dynamo or battery as may be most convenient under any given circumstances. The circuit of any selected magnet is broken or closed by a controlling lever 59 mounted upon the locomotive and playing over a bracket 60 carrying contact plates 61, 62, 63, 64 and 65 arranged in an arcuate series concentric with the fulcrum of the lever and each connected with one of the magnets. The bracket 60 is of insulating material and the main body 66 of the lever is of metal constituting a good conductor. The body 66 is formed with an eye at its lower end encircling a stud projecting from a fulcrum plate 67 which is firmly secured to the bracket 60 at the lower edge of the same, and a screw 68, inserted through the eye and into the end of the fulcrum stud, serves to secure the lever thereon and also clamp to the lever the terminal of a conductor 69 which leads from the generator. Wires 70 extend from the several contacts 61, 62, 63, 64 and 65 to the respective magnets, as will be understood upon reference to Fig. 2, so that, when the lever is in engagement with any one of the contacts, the magnet occupying the corresponding position upon the bracket 42 will be energized and the valve set accordingly. The several wires 70 extend through the cable 56 from which they branch to the magnets on the respective units of the train so that the units will be connected in multiple and will operate simultaneously. The lever 59 includes a handle 71 of insulating material, and at the base of the handle is a socket 72 accommodating a stop plunger 73 pressed outwardly by a spring 74 so that it may yieldably engage any one of the notches 75, 76, 77, 78, 79, 80 and 81 in the upper edge of the bracket 60. The body of the lever carries a carbon contact block 82 near its upper end which is pressed rearwardly by a spring 83 and is adapted to ride over the bracket and the several contacts therein so as to close the circuit through a selected contact in an obvious manner.

As previously stated, a non-return check valve 15 is inserted in the pipe 16 whereby air from the train line is supplied to the emergency reservoir. Referring to Fig. 13, it will be noted that this valve includes a casing 84 having internally threaded openings at its ends whereby it may be secured to the alined sections of the pipe and between its ends is provided with a bushing 85 forming a seat for the valve body 86, and above the valve is a grill 87 which limits the opening movement of the valve while at the same time

it is constructed to permit the flow of air therethrough. The weight of the valve tends to hold it on its seat, as shown in Fig. 13, and the pressure from the emergency reservoir 5 is applied to the top of the valve, as will be understood upon reference to Fig. 1. Whenever the pressures in the pipe 16, which is the same as the train line, and in the emergency reservoir are equal, the valve will seat under 10 its own weight, but if the pressure in the emergency reservoir should drop, the greater pressure in the train line and in the pipe 16 will unseat the valve so that air will again flow into the emergency reservoir to re-establish 15 equilibrium.

The double check valve 34 is provided at the junction of the pipes 8 and 33 with the brake cylinder and its function is to prevent flow from the pipe 8 when the brakes are 20 operated electrically and to prevent flow from the pipe 33 when the brakes are operated pneumatically. As shown in Figs. 14 and 25 15, the valve casing includes a body 88 having a threaded opening or nipple 89 whereby it may be secured upon the pipe 33 and containing a seat 90 for the valve proper. The body 88 also constructed with a threaded nipple 91 whereby it may be connected to and established communication with the brake 30 cylinder, and opposite said nipple is a threaded nipple 92 which may be closed by a plug or be fitted with a safety valve if the use of such valve be deemed desirable. Secured in the end of the body 88 opposite the nipple 35 89 is a bonnet 93 at the outer end of which is fitted a nipple 94 whereby connection with the air pipe 8 may be established and on the inner end of the bonnet 93 is a valve seat 95. Within the body or casing 88, between the 40 seats 90 and 95, is a bushing or sleeve 96 having ports 97 and 97' establishing communication between the interior of the bushing or sleeve and the chamber 98 surrounding the bushing within the casing 88, said chamber 45 being in direct communication through the nipple 91 with the brake cylinder. The valve proper consists of a piston 99 fitting closely but slidably within the bushing or sleeve 96 and provided at its ends with washers or packing elements 100, the length of the piston being less than the distance between the seats 90 and 95, as will be understood. As shown in Fig. 14, when the brakes are operated pneumatically, the pressure 50 in the pipe 8 will be greater than the pressure in the pipe 33 and, consequently, the valve will be driven to the seat 90 and flow of air from the pipe 33 will be prevented, the air from the pipe 8 passing through the ports 97 and escaping into the brake cylinder. On the other hand, as shown in Fig. 15, when the brakes are operated electrically, the pressure 55 from the pipe 33 will be greater than that from the pipe 8 and the valve will be forced against the seat 95 and the flow of

air from the pipe 8 thereby cut off, the air from the pipe 33 passing out through the ports 97' to the brake cylinder to set the brakes. The double check valve casing is arranged horizontally, as shown, in order that the piston valve will be moved only under the influence of the air admitted to the casing. 70

The cable coupling 57 is a block of insulation into which the cable 56 is fitted at its rear end and this block is preferably flared from its center toward both ends, as indicated in Fig. 16, so that it may be conveniently handled. Within the coupling body, the several wires are freed of the cable and each wire is branched within the body, as 75 shown at 101. One branch extends through the end of the coupling body is fitted with a metallic terminal 102 which is triangular in cross section while the other branch has its end secured to a metallic socket 103 within the end of the coupling body which socket is also triangular in cross section. Referring to Fig. 17, it will be noted that half of the terminals 102 are disposed with their apexes downward while the other half of the terminals are disposed with their apexes upward, and a similar arrangement exists with the sockets. Obviously, it is intended that the projecting terminal 102 be engaged in corresponding sockets 103 in the meeting coupling 80 95 body and by reversing the terminals and locating all the sockets on one side of the vertical medial line of the body and the projecting terminals all on the opposite side of said line accuracy in the coupling is insured so that 100 there can be no crossing of the circuits at any point in the system. In the end face of each coupling body, around the several terminals, is a gasket or packing strip 104 which projects slightly from the face of the body so that, when the two coupling bodies are brought together, a tight joint will be effected and moisture cannot enter the coupling to destroy 105 the efficiency of the electric contacts.

In Fig. 2, the armature arm 45 is shown in an intermediate vertical position and the slide valve 18 will then be held in the lap position illustrated in Fig. 8. When it is desired to shift the valve, the controlling lever 59 is rocked upon its fulcrum so as to bring the contact block 82 onto the selected contact on the block 60 and thereby close a circuit through the corresponding selected magnet. For instance, if it be desired to make an emergency application of the 110 brakes, the lever is rocked so that the contact block 82 will bear upon the contact 65 and thereupon current will flow from the generator over the wire 69 to the lever 66 and thence through the contact 82 and the block 65 115 to pass through the wire 70 connecting said contact block 65 with the electro-magnet 51, returning to the generator through the common return wire 55. The magnet 51 being 120 energized, the armature arm 45 will be 125 forced against the seat 95 and the lever 66 130

attracted and will swing to such position that it will be presented to the poles of said magnet, and this rocking of the arm will cause the pinion 44 to simultaneously rotate and by its engagement with the rack 41 move the slide valve to the extreme left which is the position shown in Fig. 6. In order that there may be no waste of current when the brakes are not applied, the notches 77 and 79 are provided 5 at the opposite sides of the central notch 78, and when the lever is set so that the stop plunger or dog 73 engages either of these notches 77 or 79 the block 82 will bear against the face of the insulated bracket 60 and, consequently, no current will flow. 10

The system is charged in the usual manner which has been briefly referred to. The air is compressed by the compressor 1 and passes therefrom into the main reservoir 2 which 15 stores and cools the air and from said reservoir it passes through the engineer's valve to the train line, branching from the train line at each unit through the branch 5 to charge the auxiliary reservoir through the triple 20 valve, and it is maintained in the auxiliary reservoir to pass to the brake cylinder whether the brakes be operated electrically or pneumatically. Some of the air also passes from the branch 5 into the emergency reservoir 25 and through the pipe 20, which may be called a "maintaining" pipe, inasmuch as this pipe communicates through the slide valve and the pipe 24 with the auxiliary reservoir so as to maintain the pressure there- 30 in. The air which passes into the emergency reservoir is held therein, except when an emergency application of the brakes is made, at which time it passes through the pipe 25, the slide valve and the pipe 28 directly into 35 the brake cylinder. While the system is being charged with air, current may pass from the generator to the controlling lever which is at that time set in the notch 77 and no current will then pass beyond the lever until it is set 40 to apply the brakes electrically. 45

When it is desired to make a service application of the brakes, which will bring the cars to a smooth stop without unnecessary jolting or jarring, the control lever is brought 50 over the notch 80, whereupon the circuit is closed through the contacts 82 and 64 to energize the magnet 50. The armature arm 45 is, consequently, rocked so that the slide valve is set in the position shown in Fig. 7, 55 the recess or cavity 38 connecting the ports 30 and 32 and allowing air to pass from the auxiliary reservoir 7 through the pipe 31, the stated ports and the pipe 33 to the double check valve and thence to the brake cylinder, 60 bringing about gradually a partial or full application of the brakes according to the period of time the control lever is held on the service notch. At this time the ports 26, 27, 29 and 65 35 are blanked, the ports 21 and 23 being connected and the "maintaining" pipe being

in operation. If the lever be set in the central notch 78, the valve slide will be brought to the lap position shown in Fig. 8 in which all the ports leading to and from the brake cylinder are closed and the desired pressure will be held in the brake cylinders so that a light application or a gradual release may be made. In this lap position, however, the recess or cavity 36 connects the ports 21 and 23 so that air from the branch pipe 5 flows 70 through the maintaining pipe 20, the valve and the pipe 24 into the auxiliary reservoir and the auxiliary reservoir pressure will be maintained, even though the triple valve may have moved to close the feeding groove there- 75 of. This feature of the apparatus permits a constant brake cylinder pressure to be maintained so that the brakes may be held applied as long as desired, without the alternate releasing of the brakes and recharging of 80 the system which is necessary in the pneumatic operation, and is very desirable on heavy grades. 85

To release the brakes, the control lever is set in the notch 76 so that the magnet 48 will 90 be energized and the armature arm 45 rocked to the left in the drawings and consequently, will move the valve toward the right to the position shown in Fig. 9. In this position, the ports 21, 23, 26, 27, 29 and 30 are blanked 95 but the port 32 is connected with the exhaust port 35 so that the air in the brake cylinder may escape therefrom through the pipe 33, releasing the brakes. If it be desired to make a quick or full release, the control lever 100 is placed on the full release notch 75 so that the valve will be moved to the extreme right, as shown in Fig. 10, in which position the port 32 is blanked but the port 27, which is the terminal of the pipe 28 leading from the 105 brake cylinder, is connected with the exhaust port 29 so that the air may pass quickly from the brake cylinder to the atmosphere, all other ports being blanked. To make an emergency application of the brakes, the control lever 110 is caused to close the circuit through the contact 65 and energize the magnet 51, resulting in the slide valve being moved to the extreme 115 left, as shown in Fig. 6. The port 26 leading from the emergency reservoir 14 is thus connected with the port 27 leading through the pipe 28 to the brake cylinder so that air passes directly from the emergency reservoir to the brake cylinder and effects a sudden 120 and heavy application of the brakes, all other ports being blanked. It will be noted that this action will occur regardless of how depleted the rest of the system may be as the air which enters the emergency reservoir is prevented from passing back into the train line by the non-return check valve 15 and can pass out through the slide valve only when the valve is in emergency position. 125

Inasmuch as the armature 45 is nicely balanced, it will tend to remain set in any posi- 130

tion until some other magnet is energized. When the train is running, the controlling lever is set on the notch 77, and as this movement is from either the lap position (notch 78) or release position (notch 76) the valve 5 will remain in either the lap or release position. As the normal position of the valve is release, the control lever may be set in running position after shifting the valve to release and thereby avoid the use of current, except when the valve is to be moved from one to another of its five positions.

When it is desired to hold the brakes in service position, as to prevent movement of 15 a train on a steep grade, the control lever is set on the notch 80 to apply the brakes and then shifted to the 79 thereby stopping the flow of current. The armature and valve will then remain in service position until the 20 control lever is moved to the notch 78 or the notch 81.

In the full release position, the brake cylinder is exhausted very quickly as the air passes therefrom practically direct to the atmosphere, and the necessity for trainmen to pass along the train and open the bleeder valves on the several auxiliary reservoirs is eliminated. I thus save time and labor, avoid danger to the train crew, and overcome waste 25 of air from the auxiliary reservoir. As a complete release of the brakes is effected, there is no delay in starting a train due to brakes sticking and resulting damaged draft gear or flat wheels.

30 Having thus described the invention, I claim:

1. Means for controlling air brakes including an emergency reservoir, means for charging said reservoir from the train line of the 40 system, and means for admitting air from the emergency reservoir directly to the brake cylinders.

2. Means for controlling air brakes including pipes connecting the train line and the 45 auxiliary reservoir independently of the triple valve, pipes connecting the auxiliary reservoir and the brake cylinder independently of the triple valve, and a single controlling valve arranged to set up or cut off 50 flow through all said pipes whereby to constantly maintain the desired pressure in the auxiliary reservoir and admit pressure to or release it from the brake cylinder.

3. Controlling mechanism for air brakes 55 comprising pipes establishing communication between the train line and the auxiliary reservoir and between the auxiliary reservoir and the brake cylinders independently of the triple valve, a valve controlling flow through 60 said pipes, and means for operating said valve independently of the engineer's valve and the triple valve.

4. Means for controlling air brakes including pipes establishing communication be- 65 tween the train line and the auxiliary reser-

voir and between the auxiliary reservoir and the brake cylinders independent of the triple valve, a slide valve controlling the flow through said pipes, and electric means for setting said valve in a selected position.

5. Means for controlling air brakes comprising pipes establishing communication between the train line and the auxiliary reservoir and between the auxiliary reservoir and the brake cylinders independent of the triple valve, a slide valve controlling flow through 70 said pipes, an oscillatory armature operatively connected with said valve, a plurality of magnets arranged in an arcuate series concentric with said oscillatory armature, and means for selectively energizing the magnets whereby to set the valve in a selected position.

6. Means for controlling air brakes including pipes establishing communication between the train line and the auxiliary reservoir and between the auxiliary reservoir and the brake cylinders independently of the triple valve, a valve controlling the flow through 75 said pipes, an oscillatory armature operatively connected with said valve, a plurality of magnets arranged to act on said armature, a source of electric energy, and a control lever arranged to selectively energize and de-energize said magnets.

7. Means for controlling air brakes comprising pipes establishing communication between the train line and the auxiliary reservoir and between the auxiliary reservoir and the brake cylinders independently of the triple valve, a valve controlling the flow through 80 said pipes, an oscillatory armature operatively connected with said valve, a plurality of magnets arranged to act on said armature, a source of electric energy, a common return from the magnets to said source, 85 a plurality of contacts remote from the magnets, conductors connecting each of said contacts with one of the magnets, a control lever arranged to move over said contacts and establish electric connection with any one thereof, and a conductor leading from the source of electric energy to said control lever.

8. Means for operating air brakes in addition to and independently of the pneumatic means comprising an emergency reservoir, a connection between said reservoir and the brake cylinder, a valve controlling flow through said connection, means for setting said valve, a connection between the emergency reservoir and the train line, and a check valve inserted in said means and seating by gravity whereby to open when the pressure in the reservoir falls below the pressure of the train line.

9. In an air brake system, the combination of a brake cylinder, a triple valve, an auxiliary reservoir and a pipe leading from the triple valve to the brake cylinder, of a second pipe leading from the auxiliary reser- 125

voir to the brake cylinder, an electrically operated valve controlling the flow through said pipe, and a double check valve at the brake cylinder comprising a casing having a port connected with the brake cylinder and ports connected with the pipes leading from the triple valve and from the auxiliary reservoir respectively, valve seats at opposite sides of the port leading to the brake cylinder, and a piston valve playing between said seats.

10. In means for controlling air brakes electrically, a cable conducting the operating current, coupling bodies each receiving said cable through one end and provided at its opposite end with a plurality of sockets arranged in alignment, the conductors being branched within the coupling body and each having one branch electrically connected with one of said sockets and the other branch provided with a terminal projecting from the body, the sockets and the terminals being of triangular formation with their apexes reversed and all the sockets being on one side of a central line and all the terminals on the other side of a central line whereby the sockets and terminals of opposed couplings will be properly engaged.

11. In an air brake system including a train line, a triple valve, and an auxiliary reservoir, means for by-passing air around the triple valve from the train line to the auxiliary reservoir, a valve controlling flow through said by-passing means, and means extraneous to the by-passing means for setting said valve.

12. In an air brake system including an air supply and a brake cylinder, a plurality of air passages independently connecting the air supply with one end of the brake cylinder, a valve casing having a line of ports in one side, some of said ports forming parts of the respective air passages and other ports constituting exhausts, a slide valve having recesses in its under side adapted to selectively connect certain of the ports to effect quick or slow application or release of the brakes, and electro-magnetic means for setting said valve.

In testimony whereof I affix my signature.
LESLIE D. BOWER. [L.S.]
